COMBINATION NURSERY CHAIR
AND STEP-STOOLCharles T. De Puy, Brighton, N. Y., assignor to
Trimble, Inc., Rochester, N. Y., a corporation
of New York

Application July 8, 1950, Serial No. 172,686

8 Claims. (Cl. 4—254)

1

This invention relates to a combination nursery chair and step-stool and has for its purpose to provide a support that rests on the floor and straddles an adult toilet bowl in conjunction with an infant's toilet set that is positionable on the support above the toilet bowl.

Various types of infant's toilet seats have been designed for attachment to an adult toilet seat but these have the objection that the infant's seat sometimes becomes accidentally displaced on the adult seat, also that the fastening devices which hold the infant's seat in place deface the paint, enamel or other coating or surface of the adult seat, and it is a particular purpose of the invention to afford a nursery chair with an infant's toilet seat readily positionable above an adult toilet bowl without the necessity of fastening the infant's seat on the adult seat, and which holds the infant securely and safely, with no possibility of the child falling or the chair collapsing.

A more particular purpose of the invention is to afford a foldable support consisting of leg frames that straddle an adult toilet bowl and extend thereabove, enabling the infant's seat to be positioned above the toilet bowl, and providing a support that can be more easily positioned for use than when attached to the adult seat and also readily and compactly folded for storage when not in use or for transporting in an automobile or otherwise.

Another object of the invention is to afford a step-stool including a support with a plurality of vertically spaced steps together with a toilet seat and cover, the toilet seat cover being arranged for positioning at one elevation above an adult toilet bowl for use by an infant or as a step-stool, and at another elevation where the toilet seat cover when lowered affords a step-stool which enables a child to stand on the toilet seat cover between the arms of the support for convenient access to a wash basin.

An additional object of the invention is to provide a foldable structure which can be economically manufactured and is of light weight, enabling readily folding the parts for convenience in packing or carrying when not in use.

To these and other ends, the invention consists in the construction and arrangement of parts that will appear clearly from the following description when read in conjunction with the accompanying drawings, the novel features being pointed out in the claims following the specification.

In the drawings:

Fig. 1 is a view in side elevation showing one practical embodiment of the invention, with the support straddling a toilet bowl and the infant's toilet seat in its uppermost or operative position;

Fig. 2 is a plan view of the same;

Fig. 3 is a view in rear elevation of the parts in the positions illustrated in Figs. 1 and 2;

Fig. 4 is a view in front elevation of the same;

Fig. 5 is a view in side elevation showing the toilet seat in its lower position with the toilet seat cover aligned with the uppermost step for use as a step-stool at a wash basin;

Fig. 6 is a similar view with the toilet seat in its uppermost position and the cover lowered for use as a step-stool, the cover serving as a third step;

Fig. 7 is a detail sectional view on line 7—7 of Fig. 2, and

Fig. 8 is a side elevation showing the position of the parts when folded.

The purposes of the device may be attained with various structures of which the one herein illustrated is a practical example, and referring more particularly to the drawings in which like reference numerals refer to the same parts throughout the several views, the support shown includes a generally U-shaped front leg frame of tubular or cylindrical aluminum or other metal stock consisting of front legs 1 and 2 connected by a bottom portion 3, the legs 1 and 2 terminating in arms or upper portions 4 and 5 which are pivotally connected to the rear leg frame that is of inverted, generally U-shaped formation made from tubular or cylindrical aluminum or other metal stock and including legs 6 and 7 and a connecting top portion 8. The front and rear legs 1, 2, 6 and 7 are so spaced as to straddle an adult toilet bowl, and extend above the bowl, to enable positioning an infant's seat thereabove.

9 and 11 designate toggle bars arranged on both sides of the leg frames connecting the front and rear legs, each toggle bar 9 being connected to a front leg, each toggle bar 11 being connected to a rear leg, and the toggle bars being pivotally connected to each other at 12, while 13 designates an angle plate secured to each forward toggle bar 9 and engageable with the connected rear toggle bar 11 to limit their downward movement and retain the toggle bars in horizontal relation, as shown in Fig. 1, while permitting them to fold upwardly when the support is folded or collapsed. Each forward toggle bar 9 is provided with a recess or notch 14 to receive and support the toilet seat when in its lowermost position as will be described more fully presently.

The toilet seat may be supported on the leg frames in various ways and in the embodiment illustrated, there is provided a bail that includes end portions 15 pivotally supported in openings in the rear legs 6 and 7 while 16 designates an offset central portion of the bail on which is mounted the infant's toilet seat and toilet seat

cover. The toilet seat is indicated at 17 and has attached thereto at its side edges the hinge plates 18 which include downwardly extending portions 19, see Fig. 1, that are pivotally mounted on the offset central portion 16 of the bail, and upwardly extending portions 21 to which is pivoted a cover 22.

At its forward portion, the toilet seat 17 is provided on its underside with a transversely extending rod 23, see Figs. 2 and 4, attached in any suitable manner as by metal clips 24, and the rod 23 extends laterally beyond the seat sufficiently to engage supporting devices and to retain the seat at either of its two elevations. When in its uppermost position above the adult toilet bowl, the rod 23 engages and rests in brackets 25 that are attached to the front legs 1 and 2, the heads 26 at the ends of rod 23 acting to prevent lateral displacement of the rod from the brackets 25 and thus to retain the toilet seat in its uppermost position where it is supported at its rear by the pivoted bail already described, as shown in Figs. 1 and 6. With the toilet seat in this position, the cover 22 can be elevated and the device is ready for use by an infant in conjunction with an adult toilet bowl. The seat 17 is also provided on its underside with suitable cleats or supporting plates 27 to receive a detachable chamber if desirable, and when the cover 22 is lowered to the position illustrated in Fig. 6, the device may be used as a step-stool, the cover 22 serving as a top step for standing thereon.

In order to accomplish the purpose of a step-stool, there are provided two vertically spaced steps between the front legs 1 and 2, the lowermost step being indicated at 28 and having attached thereto metal clips 29 which support the step and are secured to the sides of the front legs. The clips 29 have lugs 31 struck therefrom to engage the front surfaces of the legs and hold the step rigidly attached to the legs, while 32 designates the upper step that has metal clips 33 secured thereto. The metal clips 33 are provided with curved or bent portions 34 which embrace the curved surfaces of the legs and are held in place by fastening bolts 35 secured to the front legs, while 36 designate thumb nuts engaging the bolts 35 and acting when tightened to hold the curved portions 34 of the plates in position to embrace the curved surfaces of the front legs and thus hold the upper step 32 at an angular or inclined position, as shown in Fig. 1 in full lines, to support the feet of an infant when occupying the toilet seat. When the step 32 is not to be used in this fashion, the thumb nuts 35 are loosened, permitting the step to be moved down to the horizontal position shown in Figs. 5 and 6, and in dotted lines in Fig. 1, the step being retained in this position by means of the lugs 37 struck from the clips and engaging the front surfaces of the legs to limit downward movement of the step.

The steps 28 and 32, see Figs. 5 and 6, are thus in position to function as a step-stool when the device is placed in front of a wash basin to enable a child to step up to a level above the floor to a convenient position while washing the hands. For this purpose, the seat 17 is elevated slightly at its front end from the position of Fig. 1 to disengage rod 23 from the brackets 25, and the seat is then moved rearwardly and downwardly while maintaining it in a generally horizontal position until it occupies the position shown in Fig. 5, the bail during such movement swinging from the position of Fig. 1 rearwardly and downwardly in

an arcuate path until it reaches approximately the position illustrated in Fig. 5. The rod 23 can then be engaged with the recesses 14 in the toggle bars 9, the recesses 14 serving to retain rod 23 against forward or rearward movement, and the seat 17 is retained by its weight in the position illustrated in Fig. 5.

The cover 22, when lowered while the seat is in the position illustrated in Fig. 5, occupies a position with its top surface in a plane with the top surface of the uppermost step 32 so that a child can step from the floor onto step 28, thence on to step 32, and can stand on the cover 22 between the arms 4 and 5 of the front leg frame.

A flexible strap 38 is attached to the rod 23 of the seat and engageable at its end with a snap-fastener on the seat cover 22. In order to fold or collapse the structure, the cover 22 is first lowered to the position shown in Fig. 6 and the strap 38 attached to the cover as shown in Fig. 8, whereupon the seat and cover can be swung as a unit upwardly to the approximate position illustrated in Fig. 8. Movement of the cover and seat is limited by the heads 26 on rod 23 engaging the rear legs 6 and 7, after which the toggle bars are moved upwardly at their pivotal connections, and the front leg frame folded against the rear leg frame in the manner illustrated in Fig. 8. With the parts in this position, the device can be readily carried by gripping the top portion 8 of the rear leg frame.

While the invention has been described with reference to the particular construction herein shown, it is not limited to the exact arrangement or details disclosed, and this application is intended to cover such modifications or departures as may come within the purposes of the invention and the scope of the following claims.

I claim:

1. The combination with a collapsible support comprising pivotally connected front and rear leg frames which while resting on a floor are adapted to straddle an adult toilet bowl and extend thereabove when an infant's toilet seat is in its uppermost position, of an infant's toilet seat pivotally mounted on one of said leg frames and positionable either above the adult toilet bowl or in a lower position when the device is to be used as a step-stool, and supporting means above said adult toilet bowl on the other leg frame, the infant's toilet seat being detachably arranged in said supporting means when in horizontal position and being foldable on the support when the latter is collapsed.

2. The combination with a collapsible support comprising pivotally connected front and rear leg frames which while resting on a floor are adapted to straddle an adult toilet bowl and extend thereabove when an infant's toilet seat is in its uppermost position, of a supporting bail pivoted to one of said leg frames, an infant's toilet seat pivoted at its rear end to said bail and positionable either above said adult toilet bowl or in a lower position when the device is to be used as a step-stool, and supporting means on the other leg frame above said adult toilet bowl and in which the front end of said infant's toilet seat is detachably supported, when the infant's seat is in its uppermost horizontal position, said bail permitting positioning the toilet seat in upper and lower horizontal positions when the bail is swung upwardly and downwardly respectively.

3. The combination with a foldable support comprising pivotally connected front and rear leg frames which while resting on a floor are

adapted to straddle an adult toilet bowl and extend thereabove when an infant's toilet seat is in its uppermost position, vertically spaced steps connecting the legs of the front leg frame, toggle bars connecting each front leg with the corresponding rear leg and acting to maintain the leg frames in operative relation, of a supporting bail pivotally connected between the legs of the rear leg frame, an infant's toilet seat pivotally connected to said bail and positionable in an upper horizontal position above the adult toilet bowl, the infant's toilet seat being positionable in a lower horizontal position when the bail is moved downwardly, supporting means carried by the front legs and detachably engageable with the front portion of said infant's toilet seat when the latter is in its uppermost position, said toilet seat being engaged and supported at its front portion by said toggle bars when in its lowermost position, and a cover pivotally connected to said toilet seat and positioned when lowered in the same horizontal plane with the uppermost of said steps when the toilet seat is in its lowermost position.

4. The combination with a foldable support comprising pivotally connected front and rear leg frames which while resting on a floor are adapted to straddle an adult toilet bowl and extend thereabove when an infant's toilet seat is in its uppermost position, vertically spaced steps connecting the legs of the front leg frame, toggle bars connecting each front leg with the corresponding rear leg and acting to maintain the leg frames in operative relation, of a supporting bail pivotally connected between the legs of the rear leg frame, an infant's toilet seat pivotally connected to said bail and positionable in an upper horizontal position above the adult toilet bowl, the infant's toilet seat being positionable in a lower horizontal position when the bail is moved downwardly, supporting means carried by the front legs and detachably engageable with the front portion of said infant's toilet seat when the latter is in its uppermost position, said toilet seat being engaged and supported at its front portion by said toggle bars when in its lowermost position, and a cover pivotally connected to said toilet seat and positioned when lowered in the same horizontal plane with the uppermost of said steps when the toilet seat is in its lowermost position, the uppermost of said steps being adjustable to a position inclined to a horizontal plane to support the feet of an infant when the toilet seat is in its uppermost position.

5. The combination with a foldable support comprising pivotally connected front and rear leg frames which while resting on a floor are adapted to straddle an adult toilet bowl and extend thereabove when an infant's toilet seat is in its uppermost position, vertically spaced steps connecting the legs of the front leg frame, toggle bars connecting each front leg with the corresponding rear leg and acting to maintain the leg frames in operative relation, of a supporting bail pivotally connected between the legs of the rear leg frame and movable from an upper position above its pivotal connection to a lower position below its pivotal connection, an infant's toilet seat pivotally connected to said bail and positionable horizontally at two elevations, brackets carried by the front legs, and a rod secured to the seat and detachably engageable with said brackets, said toggle bars having recesses to receive and support said rod when the seat is in its lower position, and a cover pivotally connected to said toilet seat

positionable when lowered in the same horizontal plane with the uppermost of said steps when the toilet seat is in its lowermost position.

6. The combination with a foldable support comprising pivotally connected front and rear leg frames which while resting on a floor are adapted to straddle an adult toilet bowl and extend thereabove when an infant's toilet seat is in its uppermost position, vertically spaced steps connecting the legs of the front leg frame, toggle bars connecting each front leg with the corresponding rear leg and acting to maintain the leg frames in operative relation, of a supporting bail pivotally connected between the legs of the rear leg frame and movable from an upper position above its pivotal connection to a lower position below its pivotal connection, an infant's toilet seat pivotally connected to said bail and positionable horizontally at two elevations, brackets carried by the front legs, and a rod secured to the seat and detachably engageable with said brackets, said toggle bars having recesses to receive and support said rod when the seat is in its lower position, and a cover pivotally connected to said toilet seat positionable when lowered in the same horizontal plane with the uppermost of said steps when the toilet seat is in its lowermost position, the uppermost of said steps being adjustable to a position inclined to a horizontal plane to support the feet of an infant when the toilet seat is in its uppermost position.

7. The combination with a foldable support comprising pivotally connected front and rear leg frames which while resting on a floor are adapted to straddle an adult toilet bowl and extend thereabove when an infant's toilet seat is in its uppermost position, vertically spaced steps connecting the legs of the front leg frame, of an infant's toilet seat pivotally mounted on one of said leg frames and positionable at two elevations, supporting devices engaging the free end of the toilet seat when in said two positions, and a cover pivoted to said toilet seat and positioned, when lowered, in the same plane with the uppermost of said steps when the toilet seat is in its lower position.

8. The combination with a foldable support comprising pivotally connected front and rear leg frames which while resting on a floor are adapted to straddle an adult toilet bowl and extend thereabove when an infant's toilet seat is in its uppermost position, vertically spaced steps connecting the legs of the front leg frame, of an infant's toilet seat pivotally mounted on one of said leg frames and positionable at two elevations, supporting devices engaging the free end of the toilet seat when in said two positions, and a cover pivoted to said toilet seat and positioned, when lowered, in the same plane with the uppermost of said steps when the toilet seat is in its lower position, the uppermost of said steps being adjustable to a position inclined to a horizontal plane to support the feet of an infant when the toilet seat is in its uppermost position.
